MAGNETIC BRAKE

Clyde C. Farmer, Pittsburgh, Pa., assignor to The Westinghouse Air Brake Company, Wilmerding, Pa., a corporation of Pennsylvania

Application February 23, 1935, Serial No. 7,747

2 Claims. (Cl. 188—165)

This invention relates to the type of railway brake in which a magnetic brake shoe is normally held suspended above the rail and is adapted to be moved into engagement with the rail.

5 In one type of magnetic brake system heretofore in use the brake shoe has been suspended above the rail and has been moved to a position a short distance above the rail. The winding of the shoe was then energized and the magnetic 10 attraction of the shoe for the rail caused the shoe to move into engagement with the rail. The track shoe was secured to the vehicle in such a manner that a limited amount of movement was permitted the shoe longitudinally of the car, and, 15 when the shoe was moved into engagement with the track the shoe tended to seize the rail and to remain stationary relative to the rail and to permit the vehicle to move relative to the shoe until the limit of this movement was reached.

20 As the coefficient of friction between a shoe and the rail is relatively high when the shoe is stationary relative to the rail a sudden resistance was offered to movement of the vehicle when the limit of movement between the vehicle and the 25 shoe was reached.

This condition was aggravated when the track was worn so that the clearance between the shoe and the rail at the time the shoe had reached the position to which it was moved by the fluid 30 pressure devices or other means employed to move the shoe. Because of the distance between the shoe and the rail the flux in the shoe had to build up to a very high value before the magnetic attraction between the shoe and the rail 35 was sufficient to cause the shoe to move into engagement with the rail. When the shoe did move into engagement with the rail the shoe was held in engagement with the rail with great force because of the relatively high flux density in the 40 shoe, so that the force of friction between the shoe and the rail was relatively high, with the result that the brake took effect suddenly and with a severe jerk.

45 In another type of brake system employing magnetic track brake shoes the shoes have been moved into engagement with the track by means of fluid pressure devices, but this has not been satisfactory as movements of the track shoe as a 50 result of irregularities in the track were transmitted to the vehicle through the fluid pressure devices.

55 In addition in this system when the track shoe was moved into engagement with the track, the pressure of the fluid in the fluid pressure devices

built up and tended to lift the vehicle away from the rails.

It is an object of this invention to provide an improved brake system of the type employing magnetic track brake shoes.

5 It is another object of this invention to provide an improved braking system of the type employing magnetic track brake shoes and having means to yieldingly press the track brake shoes into engagement with the rail.

10 It is a further object of this invention to provide an improved braking system employing magnetic track brake shoes and having fluid pressure responsive means to yieldingly press the track brake shoes into engagement with the rail, while 15 at the same time employing means responsive to the pressure of the fluid supplied to the fluid pressure responsive means to control the supply of current to the track brake shoe.

20 Other objects of the invention and features of novelty will be apparent from the following description taken in connection with the accompanying drawing, the single figure of which is a diagrammatic sectional view of a magnetic brake apparatus embodying my invention.

25 As shown in the drawing the apparatus may comprise a magnetic brake shoe 1 having a suitable winding (not shown) associated therewith and being held suspended above the rail 2 by springs 4 secured to brackets 5 attached to the 30 vehicle truck frame 3. The springs 4 are strong enough to normally maintain the brake shoe 1 out of engagement with the rail 2.

35 Means is provided for moving the brake shoe into engagement with the rail, and as shown in the drawing, this means comprises a pressure cylinder 6 containing a movable abutment in the form of a piston 7 to which is secured a rod 8. The lower end of the rod 8 has an enlarged head 9 formed thereon which is positioned 40 in the spring cage 10 in engagement with a compression spring 11, mounted within the cage 10. The lower portion of the cage 10 has a rod 12 secured thereto which is pivotally secured to the brake shoe 1 by means of a pin 13.

45 During the time the air cylinder is vented the springs 4 are of sufficient strength to support the track shoe 1 above the rail. When it is desired to apply the magnetic track shoe fluid under pressure is supplied to the cylinder 6 50 through the pipe 15, to which pipe fluid under pressure may be supplied and released by any suitable controlling means. The pressure of the fluid acting upon the abutment or piston 7 forces it downwardly, and its movement is transmitted 55

through the spring 11 to the cage 10 and the rod 12 to the brake shoe 1 to press the brake shoe into engagement with the rail 2. The spring 11 through which the fluid pressure responsive 5 means operates is of sufficient strength to force the track shoe downwardly against the resistance of the supporting springs 4.

The abutment or piston 7 is preferably proportioned so that the fluid pressure supplied 10 thereto will have sufficient force to compress the compression spring 11 after the brake shoe 1 is moved into engagement with the rail 2, with the result that the piston 7 will move down into engagement with the lower end of the cylinder 15 6 which acts as a stop for the piston. The rod 8, the spring 11 and the other members employed 20 to connect the piston 7 with the brake shoe 1 are proportioned so that when the piston 7 is moved into engagement with the lower end of the cylinder 6 the spring 11 will be only partially compressed. As a result, when the track shoe is 25 moved along the rail any vibrations of the track shoe caused by irregularities or rough spots in the track will be absorbed by the spring, which serves as a cushion, and will not be transmitted to the car truck.

This construction also operates to limit the amount of force which will be applied to the track shoe to hold it in engagement with the rail. 30 This will be the force which is required to partially compress the spring 11, and this force will be substantially the same regardless of the pressure of the fluid in the cylinder 6 as an increase in the pressure in the cylinder 6 will merely cause 35 the piston 7 to be pressed against the lower end of the cylinder 6 more firmly and will not cause the spring 11 to be compressed to a greater degree. The force which is transmitted through the spring 11 is of sufficient magnitude to insure 40 that the track shoe will be moved into engagement with the rail, but is of small enough value that there is no objectionable tendency for the fluid pressure operated devices to lift the vehicle away from the rails. 45 The lower end of the rod 8 loosely fits in the opening in the upper end of the spring cage 10 so that a limited amount of movement is permitted between the spring cage 10 and the rod 8, and as a result the track shoe 1 can move a 50 limited distance either longitudinally or transversely of the vehicle without effecting movement of the piston 7. As pointed out above the spring 11 acts as a cushion and permits the shoe 1 to move a short distance vertically without moving 55 the piston 7.

A switch device for controlling the circuit to the brake shoe magnet winding is also provided, and as shown in the drawing, comprises a casing 20 containing a piston 21 adapted to seat on a seat 60 rib 22, the space within the seat rib being connected to the pipe 15.

A coil spring 23 urges the piston 21 to its seat. A vent passage 24 connects the chamber 25 outwardly of the seat rib 22 with the chamber 26 65 on the spring side of the piston 21 to prevent possible build up of fluid pressure in said chamber by leakage while the piston is in its seated position. The chamber 26 is connected to the atmosphere by way of the passage 27.

The piston 21 is provided with a stem 30, carrying at its outer end, a switch contact 31 adapted 70 when moved to the right from the position shown in the drawing to connect contacts 32 and 33 to close a circuit from a source of current, (not 75 shown), through the winding of the track shoe 1.

In operation, when it is desired to effect an application of the magnetic brake the operator supplies fluid under pressure to the pipe 15 which flows to the cylinder 6 and forces the piston 7 downwardly. Movement of the piston 7 is transmitted through the spring 11 to the brake shoe 5 which is forced downwardly against the springs 4 so as to be yieldingly pressed into engagement with the rail 2.

The switch device for controlling the circuit 10 to the winding of the brake shoe magnet is also open to the pipe 15, but owing to the restricted area of the piston 21 which is subject to the pressure in the pipe 15, when the piston is seated, and the resistance of the spring 23, the piston 21 15 will not move until the pressure of the fluid in the pipe 15 has built up to a relatively high value, which will be great enough to cause the piston 7 to shift the brake shoe 1 into engagement with the rail. 20

When the pressure of the fluid in the pipe 15 increases sufficiently to cause the piston 21 to move away from the seat rib 22 and expose the full area of the piston 21 to the fluid pressure supplied through the pipe 15 the piston is quickly shifted to the right so as to complete the circuit to the winding of the brake shoe, and also to move a seat rib 28 on the piston 21 into engagement with a sealing gasket 29 clamped between the casing section 20 and the adjoining 30 casing section so as to cut off the escape of fluid under pressure from the pipe 15 to the atmosphere by way of the passage 27. As the shoe is already in engagement with the rail before current is supplied to the track shoe winding the 35 shoe will be in motion at the time at which it is energized and this insures that the brake shoe will not be heavily energized when the brake shoe engages the rail so that the initial application of the brake will be effected very smoothly. 40

When it is desired to release the magnetic brake, fluid under pressure is released from the pipe 15 thereby causing a reduction in the pressure acting on both pistons 7 and 21. On a reduction in the pressure acting on the piston 7 this piston 45 moves upwardly due to the expansion of the partially compressed spring 11. The track shoe, however, remains in engagement with the rail as it is energized, and its attraction for the rail holds it in engagement with the rail against the springs 50 4 which tend to lift it away from the rail. When the pressure in the pipe 15 has been reduced to a predetermined value the piston 21 is moved by the spring 23 to engage the seat rib 22. This movement of the piston 21 causes the switch contacts 31 to move to the left out of engagement 55 with the contacts 32 and 33 so as to open the circuit to the winding of the track shoe. The winding thus being deenergized the magnetic attraction of the shoe for the track decreases and the 60 springs 4 then lift the shoe to its upper or release position, where the shoe is yieldingly held against the stops or brackets 40 which project from the vehicle truck frame 3 and engage the upper face 65 of the track shoe. 70

While one illustrative embodiment of the invention has been described in detail it is not my intention to limit its scope to that embodiment or otherwise than by the terms of the following claims.

Having now described my invention, what I claim as new and desire to secure by Letters Patent, is:

1. In a vehicle brake, a magnetic brake shoe normally held out of engagement with a rail, an 75

abutment movable responsive to variations in fluid pressure, means to limit the amount of movement of said abutment, means interconnecting the abutment and the brake shoe whereby the
5 shoe is movable into engagement with the rail by said abutment, said means including resiliently yieldable means through which movement of the abutment is transmitted to the shoe, means associated with said abutment and engageable
10 with said limiting means on movement of the abutment to a position to effect engagement of the track shoe with the rail, the resiliently yieldable means being arranged to yieldingly connect the brake shoe and the abutment when the abutment is held by said limiting means, whereby
15 movement of the brake shoe responsive to irregularities in the track are absorbed by said resilient means.

2. In a vehicle brake, a magnetic brake shoe, means to suspend the brake shoe above a rail, a

fluid pressure operated device for effecting movement of the shoe into engagement with a rail, said device comprising a movable abutment subject on one side to the pressure of the fluid in a chamber, yielding means comprising a pair of members and a compression spring positioned therebetween, one of said members being connected to the movable abutment, the other of said members being connected to the brake shoe, said members being urged together to effect compression of said spring on an increase in the pressure of fluid supplied to the chamber in the fluid pressure operated device upon movement of the brake shoe into engagement with the rail, and means to limit movement of the abutment whereby the movement of the members of the yielding means is limited to an amount insufficient to compress the spring to the closed position.
